UNITED STATES PATENT OFFICE

95,433

DESIGN FOR A CRAVAT HOLDER

Harold Klindt, Providence, R. I., assignor to Taunton Pearl Works, Inc., a corporation of Massachusetts

Application February 19, 1935, Serial No. 55,496

Term of patent 7 years

To all whom it may concern:

Be it known that I, Harold Klindt, a citizen of the United States of America, residing in Providence, county of Providence, State of Rhode Island, have invented a new, original, and ornamental Design for a Cravat Holder, of which the following is a specification, reference being had to the accompanying drawing forming a part thereof.

Fig. 1 is a face view of a cravat holder showing my new design; Fig. 2 is an edge view; and Fig. 3 is an end view, of the same.

I claim:

The ornamental design for a cravat holder, substantially as shown.

HAROLD KLINDT.
